FIG. 6.

FIG. 5.

FIG. 4.

Inventor:
Charles Latta,
by Ripley Kingsland,
His Attorney.

Patented Apr. 28, 1925.

UNITED STATES PATENT OFFICE.

CHARLES LATTA, OF ST. LOUIS, MISSOURI.

INTERNAL-COMBUSTION ENGINE.

Application filed May 28, 1923. Serial No. 641,849.

To all whom it may concern:

Be it known that I, CHARLES LATTA, a citizen of the United States, residing at the city of St. Louis, Missouri, have invented 5 a new and useful Internal-Combustion Engine, of which the following is a specification.

This invention relates to internal combustion engines, and an object is to provide an 10 improved mechanism for controlling the passage of gas to the engine cylinders and the exhaust therefrom.

Another object of the invention is to provide a novel and improved valve mechanism 15 and means for operating the same to obtain the desired and beneficial results herein-after disclosed.

Another object of the invention is to provide an improved valve comprising a pair 20 of cooperating valve elements having a novel construction and relationship; and means for operating them so that they will control the admission of gas to a pump device and the passage of the gas from the 25 pump device to the working cylinder.

Another object of the invention is to provide an improved valve constructed and arranged as last above stated, and in addition to provide means whereby the operation of 30 the valve will force clean air through the working cylinder for scavenging purposes.

Other objects will appear from the following description and the annexed drawings, in which

35 Fig. 1 is a horizontal sectional view showing the relationship of the pump and piston cylinders and the valve which controls the admission of gas to the pump, the passage of gas from the pump to the working cylinder and the forcing of air through the working cylinder for scavenging purposes.

40 Fig. 2 is a vertical longitudinal sectional view showing the construction and arrangement of the valve, and the position of the parts when the working cylinder is receiving gas from the pump, the working piston being on the upward stroke.

45 Fig. 3 is a sectional view at right angles to the section of Fig. 2, being taken through the valve cylinder.

50 Fig. 4 is a sectional view similar to Fig. 2, the parts being shown in the position in which gas is being admitted to the pump from a carburetor.

55 Fig. 5 is a sectional view similar to Fig.

4, the parts being shown in the positions they occupy at the time of firing.

Fig. 6 is a sectional view similar to Fig. 5, with parts shown in the position they occupy while exhaust gases are passing 60 from the working piston.

As shown my improved engine comprises a working cylinder 1 in which the working piston 2 operates, the same being connected with the crank shaft 3 by a piston rod 4; a 65 pump cylinder 5 in which the pump piston 6 operates, the same being connected with the crank shaft 3 by a piston rod 7; and a valve cylinder 8 located between the working and pump cylinders and containing valve 70 mechanism operated by the crank shaft 3 to control the admission of gas to the pump cylinder, the passage of gas from the pump cylinder to the working cylinder, and the 75 forcing of air through the working cylinder for scavenging purposes.

A gas inlet passage 9 (Figs. 1, 4 and 5) opens into the valve cylinder 8 and a port 10 forms a communication between the valve cylinder 8 and the pump cylinder 5 and 80 serves the double purpose of admitting gas into the pump cylinder from the passage 9 and permitting the gas to be forced out of the pump cylinder through the valve device 85 into the working piston cylinder. A passage 11 opens from the valve cylinder into the working piston cylinder.

85 A sliding sleeve valve member 12 operates within the valve cylinder and is restricted by an eccentric 13 on the crank shaft 3 and 90 a connection 14 from said eccentric to said sleeve. The sleeve 12 has a port 15 that registers with the passage 9 at the same time that a similar port 16 registers with the port 10 in order to admit gas into the pump cylinder (Figs. 4 and 5). When the gas is being taken into the pump cylinder the port 11 is closed by the sleeve 12. The sleeve 12 has a port 17 that is brought into registration with the port 10 at the same time that 95 a similar port 18 in the sleeve is brought into registration with the port 11 for the purpose of permitting the gas to be forced from the pump cylinder into the working piston cylinder (Fig. 2).

100 A cooperating valve member is operatively mounted in the sleeve 12, the same comprising a body 19 having a piston head 20 united with the upper end thereof by a reduced connection 21 leaving an annular 105

space between the end of the body 19 and the piston head 20. The piston head 20 is preferably equipped with an expanding piston ring 22 to form a seal to prevent passage of gas around the piston head. The valve member now being considered is operated by connections from the crank shaft 3, said connections comprising an eccentric 23 and a connection 24 therefrom to the body 19. When the sleeve 12 is in the position to admit gas from the passage 9 to the pump cylinder 5 through the ports 15 and 16, the valve member 19 is in position to permit the passage of the gas through the annular space between the upper end of the body 19 and the piston head 20 (Figs. 4 and 5).

The valve member 19 has a passage 25 therethrough which registers with the ports 17 and 18 when said ports register with the ports 10 and 11, thereby permitting the gas to pass from the pump cylinder to the working cylinder (Fig. 2). The operating connections for the sleeve valve member 12 and the valve member 19 are arranged in a relationship to effect relative movement of said valve members to obtain the positions shown so that (Fig. 2) when the gas is passing from the pump cylinder to the working cylinder the passage 9 is closed; and when gas is being taken into the pump cylinder (Figs. 4 and 5) the ports 11, 17, 18 and 25 are closed; and when the working cylinder is exhausting and being scavenged the passage 9 is closed by the sleeve 12 and the ports 17 and 18 are closed by the valve member 19 (Fig. 6).

The valve cylinder 8 is provided with an air inlet pipe 26 equipped with a check valve 27 of a type to permit air to be drawn into the valve cylinder and to prevent air from being forced from the valve cylinder through said pipe 26. A pipe 28 has one end opening into the valve cylinder 8 and the other end opening into the working cylinder 1, as shown at 29, (Fig. 6) and is equipped with a check valve 30 of a type to permit air to be forced from the valve cylinder and to prevent air from being drawn therethrough into the valve cylinder. Thus, the valve mechanism controlling the intake of gas also functions as a pump device to force air into the working cylinder across the upper end of the piston 2 and these parts are arranged in such relationship that a jet of fresh air is forced into the working cylinder at the time that exhaust is taking place. This serves to scavenge the working cylinder and piston and maintain them in a clean condition. During the scavenging of the working cylinder, the sleeve 12 and the valve member 19 occupy positions to close the intake passage 9 and to close communication between the pump cylinder and the working cylinder (Fig. 6).

From the foregoing it will be seen that

my invention is of a highly efficient character and that it obtains all of its intended objects efficiently and satisfactorily. The shape and the dimensions of the parts are comparatively unimportant, though, preferably the ports 17 and 18 are restricted in comparison with the ports 10 and 11 in order to force the gas through restricted passage into the working cylinder.

I contemplate such variations in the construction and arrangement as may be deemed expedient to obtain best results in particular cases, and I do not restrict myself un-essentially in any particular.

What I claim and desire to secure by Letters Patent is:—

1. In an engine, the combination with a working cylinder and a pump cylinder, of a valve comprising a sliding sleeve, a separate valve member mounted for relative sliding movements in the sleeve, and means for operating said sleeve and said valve member to control the passage of gas to the pump cylinder and the passage of gas from the pump cylinder to the working cylinder.

2. In an engine, the combination with a working cylinder and a pump cylinder, of a valve comprising a sliding sleeve, a separate valve member mounted for relative sliding movements in the sleeve, and means for operating said sleeve and said valve member to control the passage of gas to the pump cylinder and the passage of gas from the pump cylinder to the working cylinder and to force fresh air into the working cylinder during exhaust.

3. In an engine, the combination of a working cylinder having an inlet port, a pump cylinder having a port opening into it, a valve cylinder having a port opening into it, a sleeve mounted for sliding movements in the valve cylinder having ports for registration with the first-named three ports respectively, a valve member mounted for relative sliding movements in the sleeve and having a port for communication with two of the ports in the sleeve when said two ports are in communication with the ports opening into the working cylinder and the pump cylinder, and means for operating said sleeve and said valve member to effect the registration of said ports as aforesaid and also to close said ports.

4. In an engine, the combination of a working cylinder having an inlet port, a pump cylinder having a port opening into it, a valve cylinder having a port opening into it, a sleeve mounted for sliding movements in the valve cylinder having ports for registration with the first-named three ports respectively, a valve member mounted for relative sliding movements in the sleeve and having a port for communication with two of the ports in the sleeve when said two ports are in communication with the ports opening

- into the working cylinder and the pump cylinder, means for operating said sleeve and said valve member to effect the registration of said ports as aforesaid and also to close 5 said ports, and an air pump device operated by said valve member to force air into the working cylinder.
5. In an engine, a working cylinder, a pump cylinder, a valve cylinder between the working and pump cylinders and having ports opening into said cylinders, a sleeve mounted in the valve cylinder having ports adapted to be brought into and out of registration with the ports opening into said cylinders 10 respectively, and a valve member mounted for relative sliding movements in said sleeve and having a passage therethrough adapted to be brought into and out of registration with certain of the ports in said sleeve, and 15 means for operating said sleeve and said valve member for said purposes.
6. In an engine, a working cylinder, a pump cylinder, a valve cylinder between the working and pump cylinders and having 20
- ports opening into said cylinders, a sleeve 25 mounted in the valve cylinder having ports adapted to be brought into and out of registration with the ports opening into said cylinders respectively, a valve member mounted for relative sliding movements in said sleeve and having a passage therethrough adapted to be brought into and out of registration with certain of the ports in said sleeve, and a valve member for said purposes, and an air 30 pump device operated by said valve member for forcing air into the working cylinder during exhaust.
7. In an engine, a working cylinder, a valve cylinder having a port opening into 35 the working cylinder, a pair of relatively movable valve elements in the valve cylinder controlling the passage of gas through said ports into the working cylinder, and means operated by said valve elements for forcing 40 air through the working cylinder after each explosion and before another gas admission.

CHARLES LATTA.
